(57) **CLAIM**

The ornamental design for a fan, as shown and described.

DESCRIPTION

FIG. 1 is a top-front perspective view of a fan showing our new design;

FIG. 2 is a top view of the fan of FIG. 1.

FIG. 3 is a bottom view of the fan of FIG. 1; and,

FIG. 4 is a right side view of the fan of FIG. 1, with the left side view, front view, and rear view being the same.

The dash-dash broken lines in the drawings illustrate portions of the fan that form no part of the claimed design.

The blades of the fan are identical to each other.

The surface line shading is included for clarification purposes.
